UNITED STATES PATENT OFFICE

WALTER M. FULLER, OF CHICAGO, ILLINOIS

CLOTH AND ITS MANUFACTURE

No Drawing.

Application filed May 23, 1925. Serial No. 32,502.

Many persons, particularly those of sedentary occupations requiring much sitting in chairs and at desks, fail to secure the full value of their outer woolen garments because the latter, by reason of the objectionable shiny appearance which they develop due to rubbing on these articles of furniture and otherwise, have to be discarded before they are really worn out or useless.

10 The present invention aims to provide woolen cloth for outer garments and analogous uses in which this weakness or defect is substantially reduced or entirely eliminated, thus enabling the garment made of 15 the improved cloth to give full value and increased service.

In other words, one of the prime objects of the invention is to supply a woolen or other similar cloth which will not unduly 20 shine or become objectionably glossy by reason of the performance of its ordinary or usual service, or at least in which such tendencies are materially lessened.

25 By the term "woolen cloth" I mean all such cloths, whether technically called woolsens or worsteds or otherwise, which are made wholly or partly of wool or similar material, such as, for example, camel's hair.

Oddly enough, in the new and improved 30 non-shining or non-glossing cloth, at least in its present preferred form, I employ a shiny material, for example, silk or its equivalent.

One would not naturally turn to a lustrous 35 material of this type for use in a cloth designed especially not to become easily or normally shiny, but no difficulty will be encountered in understanding why the glossy silk, or its equivalent, is employed from the following description of the invention.

Wool naturally contains a certain amount 40 of oil, fat, or grease which preserves its pliability and flexibility, otherwise, it would be hard, harsh and brittle.

45 A quantity of such oil, or its equivalent, is present or retained in the wool of woolen cloth for this purpose, the amount depending upon several factors, including the nature of the wool, the weave of the cloth, etc.

50 In scouring or cleaning the wool during

its preparation for use in cloth this natural oil or grease is removed to a more or less degree, and the oil, or its equivalent, in required amount, is added after such scouring to keep the wool in proper condition for 55 the production of the cloth and to permit the latter to possess good wearing qualities and to present a proper appearance.

Thus, by reason of the presence of such oil or grease in the wool, the strands thereof in 60 woolen cloth are more or less shiny and brilliant, otherwise the cloth would look dull or dead.

Hence ordinary woolen cloth has a certain amount of desirable lustre or sheen, due to 65 the oil thereof present for such purpose, but more particularly to preserve its flexibility or pliability.

The shine or gloss which develops on a 70 woolen fabric during service is apparently due more or less to this oil or grease which is brought to the surface by the animal heat of the wearer of the garment and by the heat arising through the friction to which the cloth is subjected, as by rubbing on the 75 seats or arms of chairs or on desks or tables.

On rough cloth, with a substantial or high nap, the wearing off of the nap progressively removes or eliminates the portion of the 80 wool on which it occurs as it becomes shiny on the surface of the cloth, thus more or less eliminating the gloss by wearing off the wool on which it develops, but with a comparatively smooth cloth, the disagreeable 85 and unsightly shine occurs more readily, because the fabric is not worn down or off so much as the gloss appears.

When the nap is worn off of even an originally rough fabric, the remaining strands or 90 threads of the then threadbare goods are all more or less in the same plane or parallel planes on the outer surface of the goods and they for this reason collectively look shiny due to the lack of miscellaneous dispersion 95 of the light rays from their brilliant or lustrous surfaces.

Of course, when the nap is worn off of even an initially rough piece of goods, the gloss thus imparted to the cloth remains un- 100

less a new nap is raised as is sometimes temporarily done by a carding process.

A rough goods may not show the shine so readily while the nap remains thereon, because the fibers constituting the nap project or extend in many directions, and, although each one is lustrous and more or less shiny, yet the reflected light rays, by reason of the miscellaneous or heterogeneous disposition of the many projecting fiber ends, are transmitted in all directions and do not act more or less cumulatively to present a shiny appearance.

To do away with or to reduce any tendency of the goods to shine unduly, it is desirable to lessen the glossy oil content of the wool to decrease the original lustre and, at the same time, to favorably increase the brittleness of the wool fibers, whereby to modify their wearing characteristics, but a cloth composed solely of such dull, harsh and stiff strands of wool would be dead in appearance and would lack adequate pliability.

It is essential, therefore, to compensate, in some way, for such lack of lustre and to provide means in the cloth which will cooperate with such brittle and stiff wool fibers to form a cloth of reasonable and satisfactory flexibility.

In the preferred embodiment of my invention, this is accomplished by interweaving or interlacing strands or threads of silk with the woolen strands so that the silk comes to the top or face of the goods in some, but not in excessive, degree.

These smooth, shiny, silk strands, which may be either single or multiple, straight or twisted, desirably, but not necessarily, constitute a portion of both the warp and woof, that is, extend in both directions, coming somewhat to the surface, but also preferably in larger measure located at the back of the goods depending of course upon the nature of the weave.

The reason for permitting the interwoven or interlaced silk to come to the surface or outer face of the goods at intervals, in the preferred embodiment of the invention, is to make up or compensate, wholly, or in part, for the lack of shine or lustre of the wool itself due to its reduced amount of oil.

Stated differently, that portion of the shiny silk on the surface of the cloth livens up the dull or dead appearing wool of decreased oil content.

The interwoven or interlaced silk fibers or threads being strong, flexible and smooth, give the cloth the needed strength and pliability which it would not otherwise have because of the stiffness and brittleness of the unusual type and kind of wool fibers employed.

The silk itself can withstand relatively severe and sharp bending without breaking, it

has great strength, and its strands, whether straight or twisted or smooth, consequently, such silk assists in securely holding or binding the somewhat brittle interwoven wool strands together and permits the comparatively rough and harsh wool fibers to slip or slide thereon, hence affording the goods the required degree of flexibility and pliability, which the cloth, if made of the wool alone, would not have.

It may be stated succinctly, therefore, that the silk compensates for the lack of adequate lustre in the wool, it gives strength to the garment, it holds the wool fibers together, it permits play of the fibers or strands of the cloth on one another, and it gives the goods the necessary pliability.

Viewed in another way, the novel non-glossing cloth has an interwoven or interlaced silk framework in and on which the brittle, harsh and dead appearing woolen fibers are mounted, such framework affording pliability to the fabric as a whole and, because not wholly concealed, lending its lustre in a measure to the otherwise dull fabric.

In some cases, it is convenient or desirable to embody the silk strands in the wool strands, but, in such instances, it is preferable to twist the strands, yet not too tightly, whereby the silk will, at intervals, be on the surface of the goods for the reasons above indicated.

The looseness of the twist is also employed so that the silk may not merely bind the wool fibers together, but give them also a certain amount of play or slack or looseness necessary to secure the desired pliability in the goods.

In the new interwoven or interlaced silk-wool goods, owing to the abridged oil content of the wool, the tendency to shine or gloss over is correspondingly lessened, and although the wool fibers are more brittle or stiff, yet, when thus bound or tied together by the silk, they wear well, possibly better than the softer fibers of more oil, and the goods, due to the brittleness of the incorporated wool fibers, tends to wear slightly rough instead of smooth, such tendency thus aiding in the prevention of the development of the shine.

As to the amount of curtailment of the oil in the wool and the quantity of silk to be used in the interweaving or interlacing, this varies greatly, depending upon the character or nature of the wool and the type of weave of the cloth.

In some cases, the oil may be reduced to one-half that now ordinarily used under like conditions of wool and weave, but in other instances a greater or less amount may be satisfactorily employed.

The aggregate of silk to be employed is approximately that necessary to compensate

for the lack of oil, but this, of course, depends upon the manner of interweaving with the wool and other factors.

In general, the oil is decreased an amount 5 so that the quantity of silk needed will not render it unduly or objectionably conspicuous in the goods.

The incorporated silk may be of the same 10 color as the wool, or it may be of a different color or colors, the latter rendering possible the production of woolen fabrics presenting uncommonly pleasing and artistic characteristics.

If desired, the silk may be used in some- 15 what excessive degree, or, in the weaving or interlacing, it may be brought on the surface of the goods in substantial measure to give the fabric an original sheen or lustre greater than that which wool alone, as now used, 20 would have.

While I have mentioned silk specifically, as the compensating material to be employed because of the lessened quantity of oil in the 25 wool, other materials may be used with more or less satisfactory results, but so far as I know, at present, silk seems to be the best because of its qualities above noted.

I am aware that silk and wool have been used conjointly in underwear, socks, neckties, etc., but, so far as I am advised, it has 30 never been used in the manner and for the purpose herein presented.

I am further cognizant of the fact that 35 threads of silk, as stripes, have heretofore been used on the surfaces of woolen goods, but such stripes do not perform the functions of the interwoven silk strands or threads in my improved goods.

So far as my knowledge extends, there is 40 not on the market today a woolen cloth suitable for use in outer garments which has the characteristics of my novel and improved cloth produced in the manner specified.

Those skilled in this art will readily understand 45 that the invention is not limited and restricted to the precise and exact details presented because these may be modified in more or less radical degree without departure from the heart and essence of the invention and 50 without the sacrifice of any of its substantial and material benefits and advantages.

I claim:

1. In the method of making woolen fabrics, 55 the removal of a sufficient portion of the oil of the wool to reduce its flexibility and interlacing strands of such wool with compensating strands of a material of greater flexibility to give the resulting fabric adequate pliability.

2. In the method of making woolen fabric, 60 the removal of a sufficient portion of the oil of the wool to reduce its oil content below normal and thereby reduce its flexibility and interlacing strands of such wool with com-

pensating strands of silk to give the resulting fabric adequate pliability.

3. In the method of making woolen fabric, 70 the removal of a sufficient portion of the oil of the wool to reduce its lustre and interlacing strands of such wool with strands of a compensating shiny material.

4. In the method of making woolen fabric, 75 the removal of a sufficient portion of the oil of the wool to reduce its oil content below normal and thereby reduce its lustre and interlacing strands of such wool with strands of silk to compensate for the reduced lustre of the wool.

5. In the method of making woolen fabric, 80 the removal of a sufficient portion of the oil of the wool to reduce its flexibility and lustre and interlacing strands of such wool with strands of a compensating material to give the resulting fabric adequate pliability and 85 lustre.

6. In the method of making woolen fabric, 90 the removal of a sufficient portion of the oil of the wool to reduce its oil content below normal and thereby decrease its flexibility and lustre and interlacing strands of such wool with strands of silk of greater flexibility and greater lustre to compensate for the reduced pliability and lustre of the wool.

7. In the method of making woolen fabric, 95 the removal of a sufficient portion of the oil of the wool to reduce its oil content below normal and thereby decrease its flexibility and lustre and interlacing strands of such wool with strands of silk of greater flexibility and greater lustre to compensate for the reduced pliability and lustre of the wool and with a portion of the silk on the surface of the goods.

8. In the method of making woolen fabric, 105 the removal of a sufficient portion of the oil of the wool to decrease the strength of the latter and interlacing strands of such wool with strands of a material of greater strength to compensate for the reduced strength of the 110 wool.

9. A woolen fabric composed of strands of 115 wool of a pliability less than normal interlaced with strands of silk, the latter compensating for the the reduced pliability of the wool.

10. A woolen fabric composed of strands of 120 wool of a lustre less than normal interlaced with strands of silk, the latter compensating for the reduced lustre of the wool.

11. A woolen fabric composed of strands of 125 wool of a pliability and lustre both less than normal interlaced with compensating strands of silk.

12. A woolen fabric composed of strands of 130 wool of an oil content less than normal interlaced with compensating strands of silk.

13. A woolen fabric composed of strands of 135 wool of a pliability and lustre both less than normal interlaced with compensating

strands of silk which come to the front surface of the cloth at intervals.

14. A woolen cloth composed of strands of wool of a lustre less than normal interlaced with compensating strands of silk which come to the front surface of the cloth at intervals.

15. A woolen cloth composed of strands of wool of a lustre less than normal interlaced with strands of silk which come to the front surface of the goods at intervals sufficiently to compensate for the reduced lustre of the wool.

16. A cloth having at least a portion of its strands composed of twisted wool and silk.

17. A woolen cloth composed of wool the oil content of which has been reduced sufficiently to decrease its flexibility and to lessen its lustre interlaced with relatively-smooth strands of a material of greater flexibility and lustre, such material compensating for the specified diminished properties of the wool, whereby the cloth has adequate pliability and sheen.

18. A wool cloth composed of wool the oil content of which has been reduced sufficiently to decrease its flexibility and to lessen its lustre interlaced with a sufficient amount of relatively-smooth strands of a compensating material of greater flexibility and lustre to give the cloth a pliability and sheen approximating that of normal woolen cloth.

19. A wool cloth composed of wool the oil content of which has been reduced below normal sufficiently to decrease its flexibility and to lessen its lustre interlaced with a sufficient amount of compensating silk to give the cloth a pliability and sheen approximating that of normal woolen cloth.

40. In witness whereof I have hereunto set my hand.

WALTER M. FULLER.
